CHARGE FORMING DEVICE

Application filed June 12, 1929. Serial No. 370,179.

This invention relates to charge forming devices for internal combustion engines, and most particularly to that type of charge forming device which comprises a plurality of 5 primary carburetors, one for each intake port of the engine, which are adapted to deliver a primary mixture of fuel and air to a plurality of secondary carburetors located adjacent the engine intake ports where additional 10 air is mixed with the primary mixture before the latter enters the engine cylinders.

An example of a charge forming device of this type is disclosed in the application of Fred E. Aseltine, Wilford H. Teeter and 15 Carl H. Kindl, Serial No. 288,683, filed June 27, 1928.

It is the general object of the present invention to provide an improved device of the character referred to, in which the means 20 for controlling the supply of air and fuel thereto are effective to provide a mixture of the desired proportions to most satisfactorily operate the engine under all possible operating conditions.

With this general object in view, one feature of the invention consists in the provision of means for controlling the fuel supply which includes fuel supply chambers communicating with the primary carburetors and 25 to which the fuel jets deliver fuel, in combination with means for maintaining in said chambers a suction which is substantially that determined by a suction operated air valve, which controls the admission of air to the device.

A further feature of the present invention resides in the provision of primary mixture conduits lying between the primary carburetors and the secondary carburetors, which 30 comprise alternately arranged round and flat sections.

A still further feature of the invention consists of a manifold in which the primary mixture conduits are formed during the casting 35 of the manifold.

Another feature of the invention comprises improved means for controlling the operation of an auxiliary air valve which regulates the 40 supply of air to the secondary carburetors, said means comprising a dashpot and an aux-

iliary piston controlling its operation, which is adapted to be restored to its original position after each movement of the air valve, so as to retard the opening of said air valve to the same degree regardless of the position of the valve at the beginning of its opening movement.

Another feature of the invention is improved means for enriching the mixture on acceleration consisting of a pump operated on opening movement of the throttle comprising a piston which is adapted to be engaged by its operating means as the throttle is opened, but is provided with independent yielding means by which it is returned to normal position, and a well into which the pump delivers and in which atmospheric pressure is maintained at all times.

Another feature of the invention resides in the provision of means for supplying additional fuel to the fuel jets which is manually controlled so as to be operable to effect a seasonal adjustment or at any other time it may be desired to supply an enriched mixture.

Further objects and advantages of the present invention will be apparent from the following description, reference being had to the accompanying drawings wherein a preferred embodiment of one form of the present invention is clearly shown.

In the drawings:

Fig. 1 is a plan view of a charge forming device embodying this invention, the manifold being broken away in order to show the end portions thereof.

Fig. 2 is a side elevation of the device shown in Fig. 1 looking toward the engine.

Fig. 3 is a vertical section on the line 3—3 of Fig. 1.

Fig. 4 is a side elevation of the main carburetor unit viewed from the left in Fig. 1, and having parts shown in section.

Fig. 5 is a side elevation of the main carburetor unit seen from the right in Fig. 1 and being partly broken away to show certain parts in section.

Fig. 6 is a transverse, vertical section on the line 6—6 of Fig. 3.

Fig. 7 is a horizontal section on the line 7—7 of Fig. 3.

Figs. 8, 9, 10, 11, 12 and 13 are detail, fragmentary sections on the lines 8—8, 9—9, 5 10—10, 11—11, 12—12 and 13—13 of Fig. 7.

Fig. 14 is a detail view of the throttle.

Fig. 15 is a fragmentary elevation of the dashpot casting seen from the right in Fig. 4.

Fig. 16 is a fragmentary section on the line 10 10—16 of Fig. 4.

Fig. 17 is a fragmentary section on the line 15 17—17 of Fig. 7.

Fig. 18 is a detail of a valve operating connection.

15 The device disclosed herein comprises a main air manifold 10, having three outlet branches 11, 12, and 13, each of which is adapted to communicate with one of the intake ports of a multicylinder engine. These 20 branches are each provided with an attaching flange 14, which is adapted to be attached to the engine block in the usual way. Adjacent its inlet, the manifold is provided with a flange 15 to which the main carburetor unit, 25 hereinafter described, is adapted to be secured, as shown in Fig. 3.

The main carburetor unit comprises the main housing 16 in the form of a single casting having a flange 17 adapted to be secured 30 by screws 18 to the flange 15. A valve controlled air inlet coupling 19 is secured in position over an opening in the top of the housing 16 by screws 20, as shown in Fig. 1, or in any other desirable manner. A casting 21 35 having a pump cylinder and certain dashpot chambers and fuel passages formed therein as hereinafter described, is secured by screws 22 to the bottom of the main housing, a suitable gasket being provided between the castings to prevent leakage. A sheet metal fuel 40 bowl 23 is held tight against an annular surface 24 on the bottom of the main casting by a screw 25 screwed into the casting 21, a gasket 26 preventing leakage around the 45 screw.

A fuel supply line leading from a main source of fuel supply is adapted to be connected with a passage 30, formed in a boss 31 projecting from the main housing. A plug 31a normally closes another bore in the casting which communicates with the passage 30 and in which the fuel line may be connected if desired. If so connected the plug 31a may be screwed into the boss 31. The passage 30 55 is of angular form and connects at its inner end with a vertical bore 32 in the casting 21, a nipple 33 being screwed into the enlarged lower end of this bore, as indicated in Fig. 5. The passage through the nipple communicates with the passage 32 and is restricted at 60 34 to form a valve seat with which a fuel valve 35 cooperates. This valve is of square cross section as shown in Fig. 5 so as to permit a flow of fuel past the valve when the latter 65 is off its seat, and is controlled by a float 36,

secured to an arm 37, pivoted on a pin 38, supported by the casting 21 and a bracket 39 depending therefrom and integral therewith. The float controls the valve 35 to maintain a substantially constant level of fuel within the float chamber 23 in the usual manner.

A plurality of angular primary mixture passages indicated by the reference character 40, and hereinafter more fully described, are formed in the lower part of the main housing 16. Communicating with the vertical portion of the mixture passages 40 by means of orifices 41, are three chambers 42, for convenience designated fuel supply chambers. The fuel is admitted directly to these chambers 42 by means hereinafter described, and is mixed therein with a small quantity of air admitted to said chambers by means of a slot 43 formed in a partition separating the fuel chambers from a main air chamber as later described. This mixture or emulsion of fuel and air flows to the primary mixture passages 40 from said chambers 42 as hereinafter set forth. Communicating with each of the fuel supply chambers 42, are two fuel inlets 44 and 45, which are rendered effective successively in a manner to be later described, and which constitute part throttle and open throttle metering orifices respectively. The inlet 45 is in the form of a nozzle projecting into the fuel supply chamber. Fuel is conducted from the float chamber to both of these inlets through a vertical passage 46 formed in the casting 21 and illustrated in detail in Figs. 8 and 9. This passage communicates at its upper end with a horizontal fuel canal 47, which in turn communicates with both of the above mentioned fuel inlets. Fuel is supplied to the passage 46 at all times through a calibrated plug 48, having a fixed orifice therein and communicating directly with the fuel in the fuel reservoir 24. After a certain predetermined throttle movement, a valve 49 normally held closed by a spring 49a, is 100 opened by means to be later described, to permit fuel to flow from the reservoir 24 around said valve into a bore 50 in the casting 21, and thence through a horizontal passage 51 at the bottom of said casting and a metering plug 52 at the bottom of the passage 46. Additional fuel is supplied by the above described passages to provide the necessary quantity of fuel when the engine is operating at relatively high speeds. A still further means for supplying additional fuel to the inlets 44 and 45 under certain conditions, comprises a fuel passage controlled by a valve 53, operated by means later described. This valve is normally held in position to close 110 a port in the upper end of the bore 54 by a spring 55, but when the valve is depressed, fuel can pass around the valve into said bore and through a passage 56 connecting with the bottom of said bore, to a passage 57 com-

municating with the passage 47, and having a calibrated plug 58 therein to regulate the quantity of fuel supplied thereby.

The inlet 44 is provided with a restriction 560 to regulate the quantity of fuel flowing therethrough and the inlet 45 has a similar restriction 61 therein to control the fuel flow therethrough. At very low speeds, the suction within the chambers 42 is insufficient 10 to lift fuel from the top of the nozzles 45, which project into the chambers, but is enough to cause a flow from the nozzles 44, which will supply sufficient fuel to operate at such low speeds. At a predetermined speed, 15 the suction effective on the nozzles 45 becomes sufficient to draw fuel therefrom and at all higher speeds, the nozzles 45 are effective to supply the major portion of the fuel consumed by the engine. The fuel supplied 20 by the nozzles is mixed with air entering through the orifice 43 and this mixture is drawn into the primary mixture passages through orifice 41, as previously set forth. It is mixed with additional air therein and 25 is conveyed by the primary mixture conduits, hereinafter described, to the secondary mixing chambers where, under certain conditions, it is mixed with additional air to form a mixture of the desired proportions to operate 30 the engine under those operating conditions.

The primary mixture passages are controlled by a single throttle valve 65, which extends across all of the passages and is provided with grooves 66, which are adapted to register with said passages. The grooves 66 each merge into smaller grooves 67, which are adapted to provide a passage for the mixture necessary to operate the engine when idling, 40 said grooves 67 being open when the throttle is in closed position as indicated in Fig. 3. The grooves 67 are provided of as small size as possible so as to minimize dimensional errors between the individual grooves, where- 45 by the variation in area of opening between individual grooves will be as small as possible.

All the fuel supply chambers 42 communicate with a chamber 69, which for convenience may be termed a primary air chamber. The chamber 69 and fuel supply chambers 42 are separated from the main air chamber 70, hereinafter described, by means of a single partition plate 71 and the chambers 42 55 are also separated from the vertical portions of the primary mixture passages by means of a vertical partition 72, which is a part of the main casting on which the plate 71 is supported. Separating the chambers 42 from 60 each other are partitions 73, which are also a part of the main casting 16.

All the air supplied to both the air chambers 69 and 70 is admitted through the coupling 19, and is controlled by means of a 65 valve 75 normally held against its seat 76, by

means of a spring 77, which is received between the valve and a flange 78, projecting from a sleeve 79, slidably mounted on a guide sleeve 80, which is secured by any desirable means in the main housing 16. Under normal operating conditions the sleeve 79 occupies the position shown in Fig. 3, but may be lifted from this position by means of the choke mechanism so as to hold the air valve 75 closed to facilitate starting.

The choke mechanism comprises a bell crank lever 81 pivoted on a pin 82, screwed into a boss 83 formed on the main housing, or secured in position in any other desirable manner. A suitable operating connection, extending to a point convenient to the operator, may be connected to a pin 84, pivoted in the upper end of said choke lever. The upper end of said lever is bent over as indicated in Fig. 5 and the two ends of the lever are held together by means of a screw 85. The inner surfaces of the two parts of the lever 81 are threaded and engaging therewith is a stop screw 86, which is adapted to engage the main housing to determine the normal position of the choke lever. By adjusting the screw to different positions, the normal pressure of the spring 77 on valve 75 may be regulated as desired. One arm of the lever 81 extends through the wall of the main housing and is provided with a toe 87, which lies beneath flange 78 and lifts the flange and sleeve 79 when the lever is rocked in a clockwise direction, as in Fig. 6, engaging the sleeve with valve 75 to hold the latter closed. When the air valve is held closed, as described, sufficient air to carry the starting fuel from the fuel supply chambers to the engine ports is admitted through air channels 88, formed in the upper surface of the air valve 75. Also, if desired, the choke lever 81 may be provided with a flat surface 89 to admit air through the wall of the main housing when the choke lever is in its operated position.

The valve 75 admits air directly to the main air chamber 70, which supplies air to the primary air chamber 69, through slot 43 as previously described. Air also flows from the main air chamber to the secondary mixing chambers through a main air conduit 90, controlled by a manually operable valve 91, secured to a shaft 92, journaled in the main housing, and a suction operated valve 93, secured to a shaft 94, which is also rotatably mounted in said housing. The operating mechanism for these valves will be described in detail hereinafter. In addition to the air supplied to the chamber 69 and that supplied to the secondary mixing chambers, as above described, the main air chamber 70 communicates directly with the vertical portions of the primary mixture passages 40, and also supplies air, after the valve 91 begins to open, to said passages through orifices 95, which

connect each passage 40 with the secondary air conduit 90, for a purpose to be later described.

It will be noted that the slot 43 which connects the main air chamber with the primary air chamber 69, is considerably larger than the total area of orifices 41, which connect the chambers 42 with the primary mixture passages. In view of this difference in area, it will be obvious that the flow of air through the chamber 69 and the chambers 42 communicating therewith must necessarily be at very low velocity. Because of the low velocity of the air passing the fuel inlets, there is substantially no velocity head created at said inlets under any operating condition or speed. Air is admitted to the chamber 69 more rapidly than it can be exhausted therefrom, hence there is substantially no difference in the pressure maintained on opposite sides of the plate 71, which divides the chambers 69 and 70. The suction at the fuel inlets therefore, is at all engine speeds substantially the static suction of the air chamber as determined by the spring 77 which controls the opening of the main air valve.

The orifices 95 which connect the space in the passage 90 between the valves 91 and 93 with the three primary mixture passages are effective to communicate the suction of said primary mixture passages to said space and this suction will hold the valve 43 closed when the valve 91 is closed and until the pressure differential on opposite sides of the valve 93 is enough to overcome the resistance of the dashpot normally retarding the opening of such valve. These orifices therefore effect a slight delay in the opening of the valve 93 from its closed position, with respect to the opening of valve 91.

During operation at all engine speeds below a certain predetermined speed, for example, that corresponding to a vehicular speed of 20 to 25 miles per hour on a level, the mixture supplied to the engine by the primary mixture passages is of properly combustible proportions and is conveyed to the engine without mixture with additional air in the secondary carburetors. At higher engine speeds than this, the valves controlling the flow of air through the secondary air passage are opened to supply additional air and increase the quantity of mixture supplied the engine.

The valve 91 is operated by means of the primary throttle after said primary throttle has made a certain amount of independent movement subsequent to which movement the valve 91 is moved simultaneously with the said primary throttle. To this end, the primary throttle is provided with an operating arm 100, secured to the end of the primary throttle by a screw 101, and having pins 102 thereon which are adapted to be held in engagement with corresponding

recesses 102a in the end of the throttle by said screw 101. The arm 100 is provided with a hole 103 in its free end in which any suitable connection extending to a point convenient to the operator is adapted to be connected. Secured in position by the screw 101, is an arm 104 having its free end bent over, as indicated in Fig. 1, and threaded between the two parts of said arm is a stop screw 105 adapted to engage a fixed stop 106, projecting from the main housing to limit the closing movement of the throttle. By adjusting the screw 105, the normal closed position of the throttle may be regulated as desired to determine the idling speed of the engine.

Secured to the other end of the primary throttle is an operating plate 107, having pins 108 on its rear face engaging recesses in the throttle and held in position against the end of said throttle by a screw 109, which is screwed into the end of the throttle and is provided with a shoulder 110, which engages a collar 110a lying between said shoulder and the plate 107, as shown in Fig. 16. Pivotally connected to an ear 111, projecting from the operating plate 107, is a link 112, the upper end of which is provided with a short slot 113, in which is received a pin 114, projecting from an arm 115, secured to the end of the shaft 92, of the valve 91. A spring 116 engages the pin 114 at one end and the other end thereof engages a lug 117, projecting from the link 112, said spring operating to hold the parts in such position that the pin 114 normally occupies the lower end of the slot 113. The parts are so arranged that when the throttle is opened the point of connection of the link 112 with the plate 111 moves in a clockwise direction, as shown in Fig. 4, and during the first part of its movement, this point of connection moves in the arc of a circle, the center of which is the pin 114, so that while moving in this arc there is no tendency of said link to move the pin 114 and the valve 91. This movement takes place during the first part of the opening movement of the primary throttle and after said throttle has moved through a predetermined distance, the point of connection of the link 112 and the plate 107 no longer moves in an arc concentric with the pin 114 but its movement is effective to move said pin in a clockwise direction and thus move the valve 91 towards its open position.

The slot 113 is provided to prevent binding of the parts which might occur otherwise, but under normal conditions, the pin 114 is held substantially in fixed position relative to the slot by means of the spring 116. Closing or counterclockwise movement of the primary throttle and the plate 107 will obviously move the valve 91 to closed position.

The valve 93 is adapted to be opened entirely by engine suction, but until the valve

91 is opened as previously described, said valve 93 is held closed by a bifurcated lever 118, which is pivoted on the screw 109 between the head of said screw and the collar 110a as shown in Fig. 16. The lever 118 is urged toward position to hold the valve 93 by means of a spring 120, one end of which is connected to an ear 121 projecting from the member 118 while the other end is connected to a pin 122 projecting from the casting 16. In order to close the valve 93, an arm 123 is secured in any desirable manner to the valve shaft 94, and this arm is pivotally connected at its free end to a link 124, the other end of which is connected to a dashpot piston to control the opening movement of the valve 93, in a manner to be later described. The link 124 is received between the two arms of the bifurcated lever 118 and a pin 125, projecting from said link, is engaged by one arm of the member 118, when said member is moved in a counterclockwise direction to close the valve 93 and to hold such valve closed until the valve 91 is opened during the opening movement of the throttle. In order to permit the opening of the valve 93 by engine suction, it is obvious that the arm 118 must be moved out of engagement with the pin 125. This is accomplished by the throttle operating mechanism when the throttle is moved through a predetermined distance. For this purpose a pin 126 is secured to the operating plate 107 and is adapted to engage one arm of the member 118, as said plate is moved in a clockwise direction, rocking the member 118 in a clockwise direction and moving said member out of engagement with the pin 125. As the valve 93 begins to open the suction effective to open said valve is sufficient to open it against the tension of spring 120 until a predetermined engine speed is reached, but at higher speeds the position to which the member 118 is moved, as above described, determines the amount of opening movement the valve 93 may make, the engine suction being then insufficient to overcome the tension of the spring 120.

On opening movement of the throttle or the valve 91, the suction in the air chamber 70 is increased and the main air valve 75 is opened against the pressure of its spring to permit an increased flow of air past said valve. It has been found that during opening movements of said valve, it will flutter if allowed to open freely and in order to prevent fluttering, a dashpot of conventional form is provided to control the motion of said valve. The dashpot consists of a cylinder 130 formed in the casting 21 and a piston 131 secured in any desirable manner to the lower end of a stem 132 on which the valve 75 is mounted. This dashpot is of ordinary construction and is adapted to be filled with fuel from the fuel reservoir by leakage around the piston when the air valve is stationary, and through a hole 134 in the bottom of the cylinder, fuel escaping slowly from the cylinder through said hole and by leakage around said piston during opening movement of the valve whereby such opening movement is steadied.

In order to prevent a tendency of the air valve to enrich the mixture by gradually moving toward closed position because of the effect of engine pulsations at relatively low speeds the dashpot piston 131 is provided with small holes 220 therethrough and a check valve, comprising a flanged sleeve 221 closes the ports on upward movements of the air valve. The dashpot therefore resists closing movements of the valve to a greater degree than opening movements.

On opening of the throttle, it has been found necessary to provide a somewhat enriched mixture in order to properly operate the engine during the acceleration period for reasons which are well known to those skilled in this art. For this purpose, the device disclosed herein is provided with a fuel pump 85 operated by the primary throttle and designed to temporarily supply additional fuel to the primary mixture passages in the manner hereinafter described. It has also been found necessary, in order to secure the desired mixture enrichment, to provide means for retarding the opening of the valve 93 during opening movements of the main air throttle 91. This is necessary in order to produce a sufficient pressure differential between the inlet and outlet ends of the primary mixture conduits to create a velocity of flow through said conduits great enough to transport the enriched primary mixture from the fuel supply chambers 42 to the secondary mixing chambers, hereinafter described, almost instantaneously. It is a considerable distance from the fuel supply chambers to the secondary mixing chambers where the primary mixture is mixed with air flowing through the auxiliary air passage 90 and if the valve 93 were permitted to open freely, an appreciable time interval would be necessary for the rich and relatively heavy primary mixture to travel through this distance, obviously a greater time interval than that required for the pure air to travel from the air throttle 91 to said secondary mixing chambers. By retarding the opening of the valve 93, the time interval necessary for the primary mixture to reach the secondary mixing chambers is reduced, while that necessary for the air flowing past the valve 91 is increased, whereby these two intervals approach each other, in fact are substantially equalized, with the result that the enriched primary mixture and secondary air reach the secondary mixing chambers at substantially the same time.

In order to retard the opening movement of the valve 93, the link 124, hereinbefore re-

ferred to, is pivotally connected at its lower end in any desirable manner to a dashpot piston 135, which is slidable in a cylinder 136, formed in the casting 21. A valve cage 137 having a passage 138 therethrough, is secured in a plate 139, secured to the bottom of the casting 21 by screws 140, so that the passage 138 will admit fuel to the cylinder 136 from the fuel reservoir when a check valve 141, received in the valve cage, is unseated. Upward movement of the check valve is limited by a pin 142, positioned above the valve. It will be obvious that upward movement of the piston 135 is substantially unretarded as the check valve 141 is opened during such upward movement to permit the dashpot cylinder to be filled with fuel, but downward movement of the piston 135, which takes place on opening of the valve 93, is retarded to delay the opening of said valve.

In order to regulate the retarding effect of the above described dashpot so as to retard the opening of the valve to substantially the same extent at whatever position the valve may occupy when its opening movement begins, an auxiliary cylinder 143 is provided which is positioned in the casting 21 immediately adjacent the cylinder 136 and communicates therewith by the passage 144, at the bottom of said cylinder. Sliding within the cylinder 143 is a piston 145, which is normally held in the position shown in Fig. 3 by a spring 146, received between the piston and the top of cylinder 143. On downward movement of the piston 135, the piston 145 is lifted, pressure being applied to the fuel beneath said piston by means of the dashpot piston. The fuel above the piston 145 in the cylinder 143 is forced out of such cylinder during its upward movement through a small hole 147 near the top of the cylinder, and the rate of escape of fuel through such orifice determines the retarding effect of the dashpot on the valve 93. After the valve 93 has completed any opening movement, the spring 146 forces the piston 145 downwardly until it occupies the position it occupied at the beginning of the opening movement of the valve 93, and the cylinder 143 is filled with fuel from the fuel reservoir, which flows into such cylinder through the orifice 147, above mentioned. It should be clear, therefore, that the piston 145 occupies the same position whenever an opening movement of the valve 93 takes place, so that the retarding effect of the dashpot on the valve is substantially the same for every opening movement thereof.

According to this invention, the pump for supplying additional fuel to the primary mixture passages is operated by the primary throttle during its opening movement. This pump comprises a cylinder 150, formed in the casting 21 and a piston 151 which is slid able therein. The piston 151 is operated by a rod 152, pivotally connected to the pin 126,

which projects from the operating plate 107. The rod is not actually connected to the piston 151, but the lower end of such rod is received inside of a tube 153, which is secured to the piston and projects upwardly therefrom. The normal position of the rod 152 is such that the lower end of said rod is substantially in engagement with the piston 151, the piston being held in this position by a spring 154, which is received in the cylinder 150 below the piston. Obviously, since any opening movement of the throttle is effected by a clockwise movement of the operating plate 107, the rod 152 is moved downwardly and moves the piston downwardly through a corresponding distance. On closing movements of the throttle, the piston is lifted by means of spring 154, as the rod 152 is moved upward. The pump cylinder communicates with a fuel delivery conduit 155, which at its upper end communicates with a fuel well 156, formed in the casting 21. This well is open to atmosphere by means of the orifice 157, which is of larger size than the fuel delivery conduit so that atmospheric pressure is maintained in the fuel well 156 at all times. A check valve 158 is provided in an enlargement 159, at the upper end of the fuel delivery conduit adjacent its point of connection with the well 156, to prevent fuel returning to the pump cylinder when the pump is stationary or during its upward movement. The fuel flows from the well 156 to a chamber 160, formed in the casting 21 immediately adjacent the well, through three fuel passages 161. The chamber 160 is vented by means of the passage 162 which connects the top of said chamber 160 with the atmosphere, as illustrated in Fig. 7. The chamber 160 is connected with three vertical passages 163 positioned relatively close together by means of three horizontal passages 164 at the bottom of the chamber 160. The two outlet passages 163 are connected at their upper ends with channels 165, formed in the upper surface of the casting 21 and these channels communicate at their outer ends with two outer vertical passages 166, formed in the main housing 16 and communicating with the two outer primary mixture passages 40, the middle passage 163 communicates directly with the middle passage 166, which connects with the middle primary mixture passage, as indicated in Figs. 3 and 7. The fuel flows from the well 156 to the chamber 161 by gravity and in such chamber is mixed with air supplied thereto through the passage 162, to form an emulsion of fuel and air which is drawn into the primary mixture passages through the various passages above described, by the suction maintained in said mixture passages. Air is admitted through the passage 162 so that the suction in the various fuel delivery passages between the check valve and the primary mixture

passages is never sufficient to draw fuel from the pump cylinder to said mixture passages, whereby fuel is only delivered on operation of the pump. Each of the vertical passages 5 166 has a restriction 167 adjacent its outlet to regulate the flow of fuel.

The operating rod 152 for the pump piston is employed to operate the valve 49 which controls the high speed fuel inlet. For this 10 purpose an arm 170 having an ear 171 projecting therefrom, is secured to the rod 152. The ear 171 extends over the end of the valve 49 so that when the throttle is opened a predetermined amount, said ear engages the 15 valve to open it and permit a flow of fuel through the high speed inlet.

The manually operated valve 53 hereinbefore referred to, is provided primarily for the purpose of regulating the supply of fuel in 20 accordance with the seasons. Of course a somewhat richer mixture is required during cold weather than is necessary during the summer months, and means are provided to open or close this valve as desired. This 25 means comprises a cam 175 on the inner end of a short shaft 176, which is rotatably mounted in the rear wall of the main housing, as shown in Figs. 2 and 3. An operating arm 177 is secured by a screw 178 to the outer end of the shaft 176 and a spring 179 is received on the shaft between the cam 175 and the casting 16 to prevent longitudinal motion of the shaft. The arm 177 is provided with an orifice 180 in which any suitable connection extending 30 to the operator may be received. It is obvious that the cam 175 may be operated at any time to provide a somewhat richer mixture although, as above indicated, it is intended primarily as a seasonable adjustment.

40 The primary mixture passages 40 register with three primary mixture tubes 190, 191 and 192, as shown in Fig. 1. These tubes are formed of sheet metal and comprise round sections indicated at 193 and relatively flat sections 194. These tubes are positioned in the intake manifold as indicated in Fig. 1, and terminate at one end at the flange 15, where the manifold is attached to the main carburetor unit and at the other end at a point 45 adjacent the intake ports, such tubes extending centrally through the outlet branches 11, 12 and 13 of the manifold and being cast in position in said manifold during the casting of the latter. It will be observed that the round portions of the tubes 190 and 192 are situated at those points where these tubes are bent, while the round part of the tube 191 is adjacent its point of connection with its associated passage 40. The tubes are formed as 50 illustrated for a plurality of reasons. First, by making the tubes alternately round and flat, the cross sectional area of such tubes is varied throughout their length so that there is an alternate expansion and contraction of the mixture flowing therethrough, which

tends to secure a more homogeneous mixture in which the fuel content is more equally distributed than would be possible with tubes having the same area throughout their length. The flat sections of the tubes also increase the 70 velocity of flow therethrough because of a reduction in cross sectional area and since the bottom of said sections is nearly flat, the surface over which the fuel flows through the tubes is considerably increased so that there is a greater tendency to evaporation and less 75 tendency for fuel to collect on the wall of the tube. Those tubes which are bent are left round at the points where the bends are located in order to facilitate bending, and the ends of the tubes where they register with the passage 40 are also round in order to coincide with the outlet ends of such passages.

The secondary mixing chambers are located adjacent the outlet ends of the primary mixture tubes above described, and comprise means for straightening and accelerating the flow of air past the ends of said tubes. This means comprises an inner tube 200 which is spaced from the primary mixture tube and is secured by a spider 201 to an outer tube 202, which is provided with an enlargement 203 forming a shoulder 204 where it joins with the smaller portion. When the device is assembled, this shoulder 204 is adapted to be held against a corresponding shoulder 205, formed in the outlet branch of the intake manifold and the other end of the enlarged portion 202 engages a similar shoulder in the engine block. The primary mixture conduit 90 terminates about midway of the length of the inner tube so that air moving past the end of said conduit is compelled to move in a substantially straight path. While the tubes above described restrict the outlet branches of the manifold to some extent and thereby accelerate the flow at the end of the primary mixture conduits, this restriction is not as great as in earlier forms of this device where Venturi tubes have been employed surrounding the outlets of the primary mixture conduits. For this reason, there is less tendency 100 to reduce the volumetric efficiency by restriction of flow at the engine ports.

Disclosed in this application but forming no part of the present invention is a device for partially restricting the admission of air when the air valve approaches wide open position, which is provided for the purpose of enabling a relatively light spring to be used on the air valve so that the suction in the air valve chamber at relatively low speeds will not be too high and result in the formation of too rich a mixture at such speeds. The device described comprises a button 210 secured in any desirable manner to the top of the air valve stem above the air valve. As shown in the drawings this button tapers outwardly at the top so that the top is larger 110 than the bottom. The button is adapted to 120

lie opposite the restricted portion 211 of the air inlet passage after the air valve has made a predetermined opening movement, so that further opening movement of the valve will further restrict the passage. Obviously, the shape of the button may be varied to regulate the air flow as desired.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a plurality of secondary mixing chambers, a plurality of primary mixture passages adapted to deliver a primary mixture of fuel and air thereto, an air supply chamber adapted to supply air to all of said primary mixture passages, a fuel reservoir, a plurality of fuel supply chambers, one for each primary mixture passage, fuel inlets communicating with the fuel reservoir and said fuel supply chambers to admit fuel thereto, a plurality of orifices connecting the fuel supply chambers with the primary mixture passages to supply fuel thereto, and a plurality of larger orifices to connect the air chamber with each of the fuel supply chambers, whereby substantially the same suction is maintained in each of the fuel supply chambers as is maintained in the air chamber.

2. A charge forming device comprising a carburetor unit having a primary mixture passage formed therein, means for supplying fuel and air thereto, and a manifold associated with said carburetor unit having an air passage and a mixture conduit formed therein, said mixture conduit being cast entirely within the manifold walls and adapted to register with the primary mixture passage in the carburetor unit.

3. A charge forming device comprising a carburetor unit having a primary mixture passage formed therein, means for supplying fuel and air thereto, and a manifold associated with said carburetor unit having an air passage and a mixture conduit formed therein, said mixture conduit comprising a sheet metal tube cast in position entirely within the manifold walls and adapted to register with the primary mixture passage in the carburetor unit.

4. A charge forming device comprising a carburetor unit having a primary mixture passage formed therein, means for supplying fuel and air thereto, and a manifold associated with said carburetor unit having an air passage and a mixture conduit formed therein, said mixture conduit having alternate round and flat sections and adapted to register with the primary mixture passage in the carburetor unit.

5. A charge forming device comprising a

carburetor unit having a primary mixture passage formed therein, means for supplying fuel and air thereto, and a manifold associated with said carburetor unit having an air passage and a mixture conduit formed therein, said mixture conduit comprising a tube cast in position entirely within the manifold walls in position to register with said primary mixture passage and being alternately round and flat in cross section.

6. A charge forming device comprising a carburetor unit, a main air passage therein, a primary mixture passage, means for supplying fuel and air to said mixture passage, a manifold associated with said carburetor unit, an air passage therein adapted to register with the main air passage in said carburetor unit and a mixture conduit cast entirely within the manifold walls and adapted to register with said primary mixture passage.

7. A charge forming device comprising a carburetor unit having a main air passage and a plurality of primary mixture passages formed therein, means for supplying fuel and air thereto, a manifold associated therewith having a plurality of secondary mixing chambers therein to which said primary mixture passages are adapted to deliver a primary mixture of fuel and air, an air passage adapted to register with the main air passage in the carburetor unit, and a plurality of separate primary mixture conduits for conveying the primary mixture to the secondary mixing chambers, said conduits being cast entirely within the manifold walls and adapted to register with the primary mixture passages in the carburetor unit.

8. An intake manifold for internal combustion engines comprising a passage adapted to deliver air to the engine intake ports and a conduit adapted to deliver a mixture of fuel and air to said intake ports, said conduit comprising a tube cast entirely within the manifold walls.

9. An intake manifold for internal combustion engines comprising a passage adapted to deliver air to the engine intake ports and a conduit adapted to deliver a mixture of fuel and air to said intake ports, said conduit comprising a tube having alternate round and flat sections.

10. An intake manifold for internal combustion engines comprising a branched passage adapted to deliver air to all of the intake ports of a multicylinder engine, a plurality of separate conduits for delivering a mixture of fuel and air to said intake ports, said conduits being cast entirely within the manifold walls and one of said conduits being associated with each engine intake port.

11. A charge forming device for an internal combustion engine comprising an intake passage, means for supplying fuel and air thereto, a valve controlling admission of air, a dashpot for retarding the opening of the

air valve, and means for controlling the effectiveness of the dash pot comprising an auxiliary cylinder communicating with the dash-pot cylinder, and a spring controlled piston in said auxiliary cylinder.

5 12. A charge forming device for internal combustion engines comprising an intake passage, means for supplying fuel and air to said intake passage, an auxiliary air valve controlling admission of additional air to said intake passage and adapted to be opened by engine suction, a throttle regulating the flow of mixture through said passage, yielding means for preventing the opening of the 10 air valve by suction and means operated by the throttle for moving said yielding means to a position to permit opening of said valve.

15 13. A charge forming device for internal combustion engines comprising a mixture passage, means for supplying fuel and air thereto, a throttle controlling the flow therefrom, a pump for supplying additional fuel to the mixture passage on opening movements of the throttle comprising a cylinder 20 and a piston movable therein, a rod for operating said piston connected with the throttle and having no positive connection with the piston whereby on opening of the throttle, the piston is moved to pump fuel into the 25 mixture passage, but on closing movements of the throttle, the piston rod is operated independently of the throttle, an auxiliary fuel supply means for supplying additional fuel during certain operating conditions and 30 means connected to said piston rod for rendering said auxiliary fuel supply means effective.

35 14. A charge forming device for internal combustion engines comprising a mixture passage, means for supplying air thereto, fuel supply means operable to supply fuel to said mixture passage during normal operation, a pump adapted to supply additional fuel to said mixture passage on opening 40 movements of the throttle to enrich the mixture during the acceleration period, an auxiliary fuel supply means rendered effective by said pump, and another manually controlled auxiliary fuel supply means adapted to be 45 rendered effective to supply additional fuel to the mixture passage whenever it is desirable.

50 15. A charge forming device for internal combustion engines comprising a secondary mixing chamber, a primary mixing chamber in which an emulsion mixture of fuel and air is mixed with air to form a primary fuel air mixture, a mixture passage connecting said primary and secondary mixing chambers, a 55 fuel supply chamber communicating with the primary mixing chamber and supplying an emulsion of fuel and air thereto, means admitting fuel to said fuel supply chamber, an air chamber adapted to supply air to the 60 fuel supply chamber, and means for main-

taining within said fuel supply chamber substantially the same suction as is maintained in the air chamber.

16. A charge forming device for internal combustion engines comprising a secondary mixing chamber, a primary mixing chamber in which an emulsion mixture of fuel and air is mixed with air to form a primary fuel air mixture, a mixture passage connecting said primary and secondary mixing chambers, a 70 fuel supply chamber communicating with the primary mixing chamber and supplying an emulsion of fuel and air thereto, means admitting fuel to said fuel supply chamber, an air chamber adapted to supply air to 75 the fuel supply chamber, an orifice connecting the fuel supply chamber with the primary mixing chamber, and an orifice of larger size connecting the fuel supply chamber with the air chamber whereby the suction maintained in the fuel supply chamber is substantially the same as that of the air chamber.

80 17. A charge forming device for internal combustion engines comprising a secondary mixing chamber, a primary mixing chamber in which an emulsion of fuel and air is mixed with air to form a primary fuel air mixture, a mixture passage connecting said primary and secondary mixing chambers, a fuel supply 85 chamber communicating with the primary mixing chamber and supplying an emulsion of fuel and air thereto, means admitting fuel to said fuel supply chamber, an air chamber adapted to supply air to the fuel supply 90 chamber, a suction operated valve controlling the admission of air to the air chamber, and means for maintaining within said fuel supply chamber substantially the same suction as is maintained in the air chamber, whereby 95 the air valve controls the degree of suction maintained in the air chamber.

100 18. A charge forming device for internal combustion engines comprising a secondary mixing chamber, a primary mixing chamber, a mixture passage connecting said primary and secondary mixing chambers, a fuel supply chamber communicating with the primary mixing chamber and supplying an emulsion of fuel and air thereto, a plurality 105 of fuel jets for supplying fuel to said fuel supply chamber and adapted to be rendered operative successively, and means for maintaining substantially the same suction in the fuel supply chamber as is maintained in the 110 air chamber.

115 19. A charge forming device for internal combustion engines comprising a secondary mixing chamber, a primary mixing chamber, a mixture passage connecting said primary 120 and secondary mixing chambers, a fuel supply chamber communicating with the primary mixing chamber and supplying an emulsion of fuel and air thereto, means admitting fuel to said fuel supply chamber, 125

an air chamber adapted to supply air to the fuel supply chamber, an orifice connecting the fuel supply chamber with the primary mixing chamber, and an orifice of 5 larger size connecting the fuel supply chamber with the air chamber, the sizes of said orifices being such that the suction maintained in the fuel supply chamber is substantially the same as that of the air chamber under all operating conditions.

20. A charge forming device for internal combustion engines comprising an intake passage, means for supplying fuel and air to said intake passage, an auxiliary air valve 15 controlling admission of additional air to said intake passage and adapted to be opened by engine suction, a throttle regulating the flow of mixture through said passage, a member for normally preventing the opening of 20 the air valve, yielding means for holding said member in effective position, and means operated by the throttle for moving said member to ineffective position.

In testimony whereof we hereto affix our 25 signatures.
